Assistant Examiner — Anehita E. Oribabor

(57) **CLAIM**

The ornamental design for a power outlet box as shown and described.

DESCRIPTION

FIG. 1 is a top, front and right side perspective view of a power outlet box showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and right side perspective view showing the power outlet box in an open state; and,

FIG. 10 is an enlarged view of portion 10 in FIG. 9.

The broken lines in the drawings illustrate portions of the power outlet box which form no part of the claimed design. The dot-dashed lines illustrate the boundary of the enlarged view and form no part of the claimed design.

1 Claim, 10 Drawing Sheets
